UNITED STATES PATENT OFFICE.

ELIASAR KOHAN, OF PORT EWEN, NEW YORK.

WASHING-MACHINE.

1,007,450.

Specification of Letters Patent. Patented Oct. 31, 1911.

Application filed December 8, 1910. Serial No. 596,226.

To all whom it may concern:

Be it known that I, ELIASAR KOHAN, a subject of the Czar of Russia, and a resident of Port Ewen, in the county of Ulster and State of New York, have invented a new and useful Improvement in Washing-Machines; and I do hereby declare the following specification, taken in connection with the accompanying drawings, whereon the same reference characters indicate the same parts throughout, to be a full, clear, and exact disclosure of the same.

The object of my invention is to provide an apparatus which will wash clothing without rubbing, whether by mechanically operated devices or by hand. It is designed to effect the cleansing of the cloth simply by the physical action of running water and air, the water carrying a proper amount of dissolved soap, and it cleanses gently but thoroughly, without entailing the wear and tear that is usually met with when clothing or the like is washed by hand or laundered by machines. It thus effects a great saving in the labor and expense of operation.

A further object of my invention is to provide a construction whereby the above advantages can be obtained without the need of special power appliances for operating the same. It can be put into actual use at any time, merely by connecting it to a hydrant or water pipe, and can therefore be employed whenever there is occasion for its use, in any city or place having a modern water supply system.

Other objects and advantages will appear from the detailed description which follows.

On the drawings Figure 1 is an outside view of my washing apparatus; Fig. 2 is a horizontal section on the line 2—2 of Fig. 5; Fig. 3 is a plan view of the closure disk for the top of my apparatus; Fig. 4 is a horizontal section of the cleansing chamber taken on the line 4—4 of Fig. 5; and Fig. 5 is a vertical section partly in elevation, of my apparatus.

My invention comprises a bottle-shaped vessel A, which is connected at the lower portion, integrally or otherwise, to a cylindrical extension B, having a flat bottom C. The vessel A is made of sheet iron and has a perfectly smooth surface over the neck portion, but the body portion is ruffled or corrugated, as is clearly shown at c' on Figs. 4 and 5. This corrugated body portion serves as the receiving or washing chamber

for the materials to be washed, and has an opening in the side, closed by the door D. The body portion has a suitable number of holes E of equal size in its lower part, and is supported by the extension B so that its bottom is held spaced from the flat bottom C, so as to form with the extension B a space G. A suitable number of holes are also made in the sides of the extension B, and a cock H is provided on a level with the bottom C to drain the device. Above the body portion the neck A tapers for a portion of its length, and then terminates in a flaring extension I. At the junction of the tapering part of the neck with the flaring extension is a conical partition P. This partition slopes downward and outward, and has perforations P', and a flat central part O which supports a cylinder Q. This cylinder is concentric with the extension I and extends up to the top of the vessel, where it terminates in an open end. The top of the vessel A has a central opening S' therein through which the cylinder Q is inserted. The cylinder Q has lateral openings Q' near the bottom, and its lower end is pierced to receive a pipe T. This pipe has a contracted lower end with an outlet T', and contains a spiral guideway V, fitting tightly in the pipe and supported by a fixed axial stem U. The top of the pipe T has openings K and receives a tube W of rubber or metal to connect it with a water pipe or hydrant. The cylinder Q is also adapted to contain a gauze body X, which is made in sections, as shown in Fig. 2, and fits snugly around the pipe. This body X forms a holder and when the washer is in use, is filled with finely divided soap or other cleansing agent x'. The top R of the vessel contains a number of openings G', which register with corresponding openings G in a revolving closure disk Y. This disk has a central opening S, coinciding with the central opening S' in the top R, and it will be understood that the disk can be revolved so as to open or close the openings in the top of the vessel A to any desired degree, and that it is permanently secured to the vessel in any convenient way.

In operation the gauze body X is filled with sliced soap, and the clothes or cloths to be washed are put into the vessel through the door D. The tube W is then connected to a hydrant, and as the water flows in some of it passes out through the openings K,

through the soap holder, and out through the openings Q' upon the partition P, which it covers with a soap bearing film of liquid. The remainder of the water is given a whirling motion by the guide V in the pipe T, and passes out through the opening in the end of the pipe in the form of a flaring jet. This jet draws in air through the perforations P', and as the air passes through 5 the mixture of soap and water on the partition, it forms bubbles which expand downward until they come into contact with the cloth, where they are broken up. In this way the materials to be washed are covered 10 with a layer of dissolved soap, which the further action of the water forces through the texture of the material. As the bubbles are continuously formed and forced downwardly every shred and particle is subjected 15 to the action of the soapy mixture, and the dirt is gradually moistened and loosened to be carried by the water out through the holes E in the corrugated bottom. Some bubbles also form in the space G, but these 20 are washed away by the water, which finally passes out through the cock shown at H, which must be kept open during the washing. Any bubbles remaining in the space G pass out through the openings F in the 25 side of B.

I desire to emphasize the fact that the spiral guide V produces a whirling motion of the water, which serves to attract the air into the washing chamber through the perforated partition P. A stream of air, atomized water and dissolved soap is thus introduced upon the cloth or other articles to be washed. The surface of the washing chamber being made of corrugated or ruffled 30 sheet iron, the air is allowed to flow through the washing machine readily, because the ruffles keep open a number of paths beneath the cloth or the like through which the air can flow to the openings E and F and out, 35 the water passing out through the cock H, as stated above. This free flow of air is essential, as the bubbles are formed by the air passing through the partition P, and by this 40 free flow of air a continuous supply of bubbles is available and the bubbles are spread out evenly over the garments to be cleansed. I desire to cover this feature in particular 45 in some of the subjoined claims.

From the foregoing description it will 50 appear that my invention is simple and easy to use, and I desire to patent the same as broadly as possible.

Having described my invention, what I 55 claim as new is:—

60 1. In a washing device, the combination of a washing chamber, water supplying means for the said chamber, and a holder containing a cleansing agent communicating with the water supplying means and having 65 independent communication with the cham-

ber, whereby a portion of the water supply is diverted through the holder in its passage to the chamber.

2. In a washing device, the combination of a washing chamber, water supplying means for the said chamber, a holder containing a cleansing agent communicating with the water supplying means and having independent communication with the chamber whereby a portion of the water supply is diverted through the holder in its passage to the chamber; and a perforated partition between the holder and the washing chamber through which the diverted water passes. 75

3. In a washing device, the combination of a washing chamber, water supplying means for the said chamber, said means having an outlet and a holder containing a cleansing agent communicating with the water supplying means, provided with an outlet and having independent communication with the chamber adjacent the said water supply outlet, whereby a portion of the water supply is diverted through the holder in its passage to the chamber. 80

4. In a washing device, the combination of a washing chamber, water supplying means for the said chamber, said means having an outlet, a holder containing a cleansing agent communicating with the water supplying means, provided with an outlet and having independent communication with the chamber adjacent the said water supply outlet, whereby a portion of the water supply is diverted through the holder in its passage to the chamber, and a perforated partition between the holder and the washing chamber, through which the diverted water passes. 90

5. In a washing device, the combination of a washing chamber, water supplying means for the said chamber, a holder containing a cleansing agent communicating with the water supplying means and having independent communication with the chamber whereby a portion of the water supply is diverted through the holder in its passage to the chamber, a perforated partition between the holder and the washing chamber through which the diverted water passes, 100 and means affording access of air to the perforated partition. 110

6. In a washing device, the combination of a washing chamber, water supplying means for the said chamber, said means having an outlet, a holder containing a cleansing agent communicating with the water supplying means, provided with an outlet and having independent communication with the chamber adjacent the said water supply outlet, whereby a portion of the water supply is diverted through the holder in its passage to the chamber, a perforated partition between the holder and the washing chamber, through which the diverted water passes, 115 120 125 130

and means affording access of air to the perforated partition.

7. In a washing device, the combination of a washing chamber, water supplying means for the said chamber, a holder containing a cleansing agent communicating with the water supplying means and having independent communication with the chamber whereby a portion of the water supply is diverted through the holder in its passage to the chamber, a perforated partition between the holder and the washing chamber through which the diverted water passes, means affording access of air to the perforated partition, and means for causing the water to spread into a flaring jet as it is discharged into the chamber.

8. In a washing device, the combination of a washing chamber, water supplying means for the said chamber, said means having an outlet, a holder containing a cleansing agent communicating with the water supplying means, provided with an outlet and having independent communication with the chamber adjacent the said water supply outlet whereby a portion of the water supply is diverted through the holder in its passage to the chamber, a perforated partition between the holder and the washing chamber, through which the diverted water passes, means affording access of air to the perforated partition, and means for causing the water to spread out into a flaring jet as it is discharged into the chamber.

35 9. In a washing device, the combination of a corrugated washing chamber, having outlet means and a door therein, a cylindrical extension having communication with the chamber adjacent the outlet means, said

extension having a closed end and outlet means in the wall thereof, and means for supplying water and a cleansing agent to the chamber, said means comprising a water supply pipe, a holder containing cleansing agent, means for diverting part of the water through the holder, a perforated partition through which the diverted water passes, adjustable means for supplying air to the partition, and means in the supply pipe beyond the holder for giving a whirling motion to the water as it is discharged into the chamber.

10. In a washing device, the combination of a corrugated or ruffled washing chamber having outlet openings through the corrugations, a partition exposed to the outside air and having perforations leading to the washing chamber, a water pipe having a restricted nozzle and a spiral guideway therein in passing through the partition, and means for feeding a cleansing agent in solution upon the partition, whereby when the water supply is turned on the water is discharged into the chamber in a spiral or flaring atomized jet which draws air into the washing chamber through the partition, the air carrying the cleansing solution through the partition with it in the form of bubbles, and flowing unimpededly between the corrugations to the outlet openings.

In testimony whereof I have signed my name to this specification in the presence of two subscribing witnesses.
